UNITED STATES PATENT OFFICE.

UDOLPH SHERMAN, OF GIRARD, MICHIGAN.

PROTECTIVE DEVICE FOR ARTISANS.

SPECIFICATION forming part of Letters Patent No. 642,166, dated January 30, 1900.

Application filed August 14, 1899. Serial No. 727,211. (No model.)

To all whom it may concern:

Be it known that I, UDOLPH SHERMAN, a citizen of the United States, residing at Girard, in the county of Branch and State of Michigan, have invented a new and useful Protective Device for Artisans, of which the following is a specification.

This invention relates to a protective device for artisans adapted to be worn on the head and body conjointly or on the head alone; and the object of the same is to provide a device of this character adapted to prevent the inhalation of dust, particles of iron or steel, and other deleterious substances, as well as obnoxious odors, such as are encountered by grinders, miners, and operatives generally, and also to provide means for regulating the temperature of the air around the head or body in accordance with hygienic laws under certain conditions and protect workmen in pursuing certain vocations and in particular localities against surrounding health-impairing influences.

Other objects and advantages will appear in the subjoined description, and the novel features will be pointed out in the appended claim, the preferred embodiment of the device being illustrated in the accompanying drawings, in which—

Figure 1 is a sectional view of a structure, showing the air-feeding mechanism operatively disposed therein and the mode of applying parts of the device and supplying and exhausting the air therefrom. Fig. 2 is an elevation of a part of the improved helmet used in the device.

Similar numerals of reference are employed to indicate corresponding parts in both views.

The numeral 1 designates a structure or suitable frame, which may be either a part of a workshop, factory, or other building, and might also constitute the timbers within a mine. The precise or particular arrangement of the said structure is not essential and the form illustrated is used to show the practicability of the improved device, and therefore subject to such variations as the application of the apparatus may require. In the upper part or at any suitable point of the said structure a pipe 2 is located, which has one terminal projected exteriorly to give access to air, and over the said terminal a wire-gauze basket or

analogous screen device 3 is applied to prevent passage into the pipe of dust, dirt, or other matter. Adjacent this air-ingress terminal 55 of the pipe 2 a receptacle 4 is situated and adapted to contain either a refrigerating or heating medium of any suitable character, and the part of the pipe 2 which passes therethrough is formed with a coil 5 for thorough 60 circulatory purposes and to permit the material contained in the said receptacle of whatever nature it may be to thoroughly perform its function. Within the pipe 2 beyond the receptacle 4 two valves 6 and 7 are mounted at 65 a distance apart which will be of any preferred form of the two-way variety and have nozzles 8 and 9. At a point farther along on the pipe 2 are a pair of taps 10 and 11, which are spaced apart, and beyond the said taps the pipe is 70 deflected upwardly, as at 12, and again projected exteriorly to provide an egress end 13, through which the air is exhausted after use. Under the upwardly-deflected portion 12 of the pipe 2 a heat-generating medium, such 75 as a lamp 14, is located and intended to heat said part of the pipe sufficiently to create a suction and accelerate the exhaustion of the used air.

To the nozzles 8 and 9 the upper ends or 80 terminals of flexible feeding-tubes 15 and 16 are connected and run, respectively, to a helmet 17 and a body-covering garment 18. At opposite points of the helmet and body-garment exhaust-tubes 19 and 20 are attached 85 and also of a flexible nature, the opposite ends or terminals of said exhaust-tubes being connected to the taps 10 and 11. These tubes 15, 16, 19, and 20 may be of any desired length and extend away a considerable distance from 90 the pipe 2; but in all arrangements it is preferred that they depend from overhead, so that they will be kept out of the way and permit the artisan or workman attired in the helmet and garment to have free action and liberty to perform the requirements of his vocation. The helmet 17 is formed of separable sections 21, which are hinged at one side and fastened by a suitable catch at the opposite side. The front section of the helmet has 95 lights 22 therein of suitable transparent material, such as glass, to afford clear vision for the wearer of the same. The feeding-tube 16 is shown as being connected to the front sec-

tion of the helmet at a point about opposite where the nose of a wearer would be located in order to permit inspiration of the incoming air under the most favorable advantages 5 and conditions, and around the bottom portion of the helmet-sections a woolen covering-strip 23 is applied and supplied with an exteriorly-positioned elastic binding-band or analogous device 24. By this means the lower 10 part of the helmet is closely held against the neck of the wearer to prevent the ingress of surrounding dust or other deleterious particles or obnoxious odors. The body-garment 15 is firmly fastened at the wrist and ankles, and the dimensions of said garment are such that when applied sufficient room between the inner surface of the same and the wearing-apparel of the artisan will exist to permit a thorough circulation of the air around the 20 parts of the body. The helmet 17 and body-garment 18 must be applied to the person of the wearer in an air-tight manner, and the material of which the helmet and body-garment are composed must have air-tight characteristics and will be preferably rubber, rubber compound, or some other fabric supplied with a coating of suitable substance to render the same air-tight. It is also intended that the 25 neck portion of the helmet extend down over the similar part of the body-garment in order to form an air-tight joint between the two parts.

When the improved protective device is not in use, the valves 6 and 7 will be turned in 30 such manner as to shut off the pipes or tubes 15 and 16 and permit the air to pass directly out through the exhaust end 13 of the said pipe 2. When it is desired to utilize the air and feed it to the helmet and body-garment 40 after arrangement of the latter on the artisan or workman, the valves 6 and 7 are then turned to cause communication of the tubes 15 and 16 with the pipe 2 and shut off the passage of the air beyond the valve 7 through the pipe 2. 45 The air is fed through the pipes 15 and 16 into the helmet and body-garment and after serving its purpose is rapidly exhausted through the tubes 19 and 20 and part of the pipe 2 to which they are connected by the suction set 50 up adjacent the exhaust extremity of said pipe through the heating medium thereunder. The material contained within the receptacle 4 may have a cooling action on the coil 5, supply the air at a moderate temperature, or be of such a nature as to heat the incoming air. 55 This will be regulated in accordance with the locality in which the artisan is compelled to

carry on his work and whether it be in a heated enclosure or cold atmosphere.

The helmet 17 may be used alone without 60 the body-garment in carrying on grinding operations or pursuing work within an enclosure containing injurious floating or flying particles of various substances. At times it might also be desired to have several branch pipes 65 leading from the coil 5, and this would be an obvious arrangement in which a duplication only would occur. It might also be necessary at times, in view of the wide range of 70 modification of which the device is susceptible, to vary the parts to suit different applications, and therefore changes in the proportions, size, and minor details of construction may be resorted to without in the least departing from the nature or spirit of the invention. 75

Having thus described the invention, what is claimed as new is—

In a device of the character set forth, the combination of a pipe extending through a 80 building and having its opposite terminals opening out to the exterior, the one terminal of the pipe serving as the ingress and having an adjacent coil continuous with the length thereof, the opposite terminal providing the 85 egress and bent upwardly at an angle for location over a heating medium, a pair of closely-arranged valves in the pipe near the ingress terminal inside of the location of the coil, the said valves being adapted for individual use and operating to prevent the passage of air through the pipe beyond the same, articles of wearing-apparel having flexible pipes running to and connected with the said valves, the valves when operated to close the 90 pipe in which they are located providing means of communication between the said flexible pipes and the pipe in which the valves are situated, and an outlet-pipe running away from opposite portions of each of the articles 95 of wearing-apparel and attached to the pipe containing the valves at a distance from the latter so that the exhaust may take place through the pipe serving as a feed, a suction being set up by the heated extremity of the 100 pipe to facilitate the exhaust. 105

In testimony that I claim the foregoing as my own I have hereto affixed my signature in the presence of two witnesses.

UDCLPH SHERMAN.
